(57) CLAIM

The ornamental design for a dog, as shown and described.

DESCRIPTION

FIG. 1 is a quartering front elevational view of a dog
showing my new design;

FIG. 2 is a left elevational view;

FIG. 3 is a right elevational view;

FIG. 4 is a front elevational view;

FIG. 5 is a rear elevational view;

FIG. 6 is a top view; and,

FIG. 7 is a bottom view of the design of this invention.

The broken-line disclosure of elements in the views is for illustrative purposes only and forms no part of the claimed design.
